(57) **CLAIM**

The ornamental design for a cigar lighter, as shown and described.

DESCRIPTION

FIG. 1 is a perspective view of a cigar lighter according to my new design;

FIG. 2 is a front view of the cigar lighter of FIG. 1;

FIG. 3 is a top view of the cigar lighter of FIG. 1;

FIG. 4 is a right side view of the cigar lighter of FIG. 1;

FIG. 5 is a left side view of the cigar lighter of FIG. 1;

FIG. 6 is a rear end view of the cigar lighter of FIG. 1; and,

FIG. 7 is a bottom view of the cigar lighter of FIG. 1.

The broken lines in the drawings depict portions of the cigar lighter that form no part of the claimed design.
